(57) **CLAIM**

The ornamental design for a catheter assembly as shown and described.

DESCRIPTION

FIG. 1 is a front perspective view of our design for a catheter assembly;

FIG. 2 is a front end elevational view thereof;

FIG. 3 is a rear end elevational view thereof;

FIG. 4 is a top plan view thereof, the bottom plan view being a mirror image; and,

FIG. 5 is a side elevational view thereof, the other side being a mirror image.

The broken line portion of the drawings is included to show unclaimed subject matter only and forms no part of the claimed design. The catheter assembly is shown with a symbolic break in its length. The appearance of any portion of the article between the break lines forms no part of the claimed design.
